SKIRT GAUGE

Filed Jan. 3, 1929

UNITED STATES PATENT OFFICE

PHILIP SOBEL, OF SAGINAW, MICHIGAN

SKIRT GAUGE

Application filed January 3, 1929. Serial No. 330,075.

This invention relates to a skirt gauge, and has more particular reference to an improved device adapted to be used by dress-makers to facilitate basting the bottom edge portion of a skirt so that it will have a uniform length or hang evenly when worn or hung properly.

The primary object of the present invention is to provide a very simple, durable and efficient skirt gauge of the above kind embodying a vertically adjustable slide having a projecting horizontal finger adapted to form a short guide and gauge member over which the hem of the skirt may be folded.

A more particular object of this invention is to provide friction means for holding the slide in its various vertically adjusted positions, whereby manual adjustments of the slide may be expeditiously effected without time-consuming loosening of set screws, clamping screws, and the like.

Other objects will become apparent as the nature of the invention is better understood, and the same consists in the novel form, combination and arrangement of parts hereinafter more fully described, shown in the accompanying drawing, and claimed.

In the drawing:

Figure 1 is an elevational view, partly broken away, of a skirt gauge embodying the present invention.

Figure 2 is a top plan view thereof.

Figure 3 is a fragmentary detail view of the graduated upright and the slide of the device shown in Figure 1, the slide being broken away and in vertical section to reveal the friction device for holding the slide in adjusted position.

Figure 4 is an enlarged perspective view of the friction-grip member of the slide-holding device shown in Figure 3; and

Figure 5 is a view similar to Figure 3, showing a modified form of friction device for holding the slide in adjusted position.

Referring more in detail to the drawing, the present invention embodies a base 5 preferably of flat elongated form, and an upright 6 having its lower end rigidly secured as at 7 to a side edge of the base 5 intermediate the ends of the latter, the upright 6 being grad-

uated as at 8 in inches and parts thereof measured upwardly from the bottom of the base 5. A morticed slide 9 is fitted and vertically adjustable on the upright 6, and this slide has a relatively short laterally projecting horizontal finger 10 at its upper end, which is preferably of round form. The slide 9 has a friction device to hold the same in its various positions of vertical adjustment while permitting ready and quick manual adjustment of the same. The friction device may take any of many different forms, but two preferred forms thereof are shown by way of example. In the construction shown in Figures 1 to 4 inclusive, the slide has an internal recess provided at its upper portion with an outwardly inclined outer wall 11 contacted by the similarly beveled outer side of a wedge-like friction-grip member or block 12 which is vertically slidable in the internal recess of the slide. The member 12 is yieldingly urged upwardly by means of a spring 13 so as to cooperate with the inclined wall 11 and be normally forced inwardly into frictional engagement with the adjacent edge of the upright 6, thereby holding the slide against accidental movement when once adjusted to a desired elevation.

An advantage of this construction is that downward pressure on the slide 9 will cause the member 12 to tightly grip the upright 6 and prevent downward displacement of the slide unless the member 12 is intentionally depressed for its release. There is very little danger, therefore, that any adjustment of the slide will be accidentally disturbed and go unnoticed. To facilitate depression and release of the friction-grip member 12, the upper end of the latter projects above the slide 9 and has a lateral finger piece 14.

In the form of the invention shown in Figure 5, the slide 9a has an internal recess in which is seated a spring 15 forming a yielding friction-grip member constantly having frictional engagement with the adjacent edge 95 of the upright 6a to hold the slide in any of its positions of vertical adjustment. This embodiment permits free manual adjustment of the slide in either direction without the necessity of first releasing any holding mem- 100

ber, and may be used to advantage if care is taken to prevent unnoticed accidental downward displacement of the slide when the gauge is in use.

5 In using the gauge, a skirt is hung properly for turning a hem at the bottom, the gauge being placed on the floor at one side of the skirt. The slide 9 or 9a is then adjusted on the upright 6 or 6a until the top of said slide 10 coincides with the graduation on the said upright which approximately indicates the distance from the ground at which it is desired to have the skirt terminate. The adjacent lower edge portion of the skirt is then 15 folded over the finger 10 and secured in any suitable manner. This operation is repeated until the entire hem has been turned up and temporarily fastened.

20 As the gauge embodies a relatively short finger 10 instead of a long arm, the device may be conveniently packed and transported without making the finger detachable and disassembling the parts. Moreover, the slide is freely manually adjustable at all times, thus avoiding the necessity of alternately releasing and applying fastening means for the slide, an objectionable and time-consuming operation which is involved where clamping screws and the like are employed.

25 30 Minor changes may be made without departing from the spirit and scope of the invention as claimed.

What I claim as new is:

35 A skirt gauge comprising a base, an upright rigid with and rising from said base and provided with lineal graduations measured from the bottom of the base, a morticed slide fitted and vertically adjustable on the upright and having a laterally projecting 40 horizontal guide finger about which the bottom edge portion of the skirt may be turned in forming a hem, and wedge-shaped means carried by the slide having frictional engagement with an edge of the upright for holding 45 the slide in any desired position of vertical adjustment, a spring cooperating with said wedge-shaped means whereby the latter acts as a manually releasable spring-pressed friction-grip wedge for forcing the slide into firm 50 engagement with the upright in case the slide is pressed downwardly without manual depression and release of said means.

In testimony whereof I affix my signature.

PHILIP SOBEL.
